CLAIM

The ornamental design for a remote control car, as shown and described.

DESCRIPTION

FIG. 1 is a perspective view of a remote control car showing the new design;

FIG. 2 is another perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken-line boundary shown in FIG. 3 and the portions of the remote control car appearing within that boundary form no part of the claimed design.
